UNITED STATES PATENT OFFICE.

EDWARD G. HORNE, OF DURANT, INDIAN TERRITORY, ASSIGNOR OF TWO-FIFTHS TO DANIEL W. RANKIN, OF DURANT, INDIAN TERRITORY.

FENCE-BRACE.

SPECIFICATION forming part of Letters Patent No. 734,873, dated July 28, 1903.

Application filed September 18, 1902. Serial No. 123,951. (No model.)

To all whom it may concern:

Be it known that I, EDWARD G. HORNE, a citizen of the United States, residing at Durant, in the county of Blue, Indian Territory, have invented certain new and useful Improvements in Fence-Braces, of which the following is a specification.

The object of this invention is to provide a simple and inexpensive means for effectually bracing the corner-post of a wire fence.

With this and other objects, which will be disclosed in the following description, in view the invention consists of the parts and combinations of parts, as will be hereinafter described, and pointed out in the appended claims.

In the drawings forming a part of this specification, Figure 1 is a side view of a fence equipped at each end with my improved brace. Fig. 2 is a perspective view of my brace, and Fig. 3 is a top view.

Referring more particularly to the drawings, 1 indicates the corner-post, 2 the fence-wires, and 3 the ordinary fence-posts, mounted between the corner-posts. A king-post 4 is located a short distance from each corner-post 1, and an inclined brace 5 has its upper end 6 beveled and bears against the corner-post 1. The lower end of the brace 5 is beveled horizontally, as shown at 7, and vertically, as shown at 8. The horizontal bevel 7 of the brace is supported upon a block 9, resting upon the ground adjacent to the king-post 4, and the vertical bevel 8 bears against the abutment 10 on the block 9. The upper end of the inclined brace 5 is provided with a notch, as shown at 11, in which is secured an end of a wire cable 12, and the other end of this cable is connected to the adjacent end 40 of an elongated anchor 13, placed in the earth to one side of the corner-post 1 in alinement with the fence and in a position so that the cable 12 is nearly vertical, thereby obtaining a direct downward pull upon the upper end 45 of the brace. A wire cable 14 is connected at one end to the outer end of the anchor 13, and its other end is secured in a notch 15 near the top of the king-post 4. A wedge 16 is driven between the block 9 and the king-post 4.

The action of the brace is as follows: After

the brace and fencing have been built the wedge 16 is driven, which tends to raise the upper end of the brace 5. This raising of the end, however, is prevented by the brace-cable 12, which holds it down and against the corner-post 1, thereby forcing the same outwardly and stretching the wires of the fence. The king-post force acts as a brace for the brace 5 and is itself braced by the cable 14, and both cables being connected at separate points to an anchor of special construction prevent the post 1 rising out of the ground or leaning.

When two lines of fencing are connected to one corner-post, the king-post 4 may be set half-way between two lines, making one brace serve for both lines of fencing.

Various changes in form, proportion, and minor details of construction may be made within the scope of the appended claims without departing from the spirit of my invention.

Having thus described my invention, what I claim as new therein is—

1. In combination with the corner-post and a brace bearing loosely against one face of the post, of an anchor, a cable connected with the anchor and the upper end of the brace to prevent the brace sliding upwardly on the post, and means for moving the lower end of the brace toward said post.

2. The combination with the corner-post, a brace, a king-post and an anchor, of a wedge driven between the brace and the king-post, a cable connecting the king-post with the anchor, and means holding the upper end of the brace down connected with said anchor.

3. The combination with the corner-post, a brace, and a king-post, an anchor, a cable connecting the king-post and the anchor, and means holding the upper end of the brace down and also connected with said anchor, of a block, an abutment on the block against which the brace bears, and a wedge driven between the block and the king-post.

4. The combination with the corner-post, a brace, and a king-post, of an anchor, a cable connected to the upper end of the brace and to the anchor, and a second cable connected to the upper end of the king-post and to the anchor.

5. The combination with the corner-post,

a brace, and a king-post, of an anchor, a cable connected to the brace and to the anchor to hold the upper end of the brace down, and a second cable connecting the king-post and the anchor, to hold the upper end of the king-post against movement.

6. The combination with the corner-post, a brace, and a king-post, of an anchor, a cable connecting the brace and the anchor, a cable connecting the king-post and the anchor, and a wedge driven between the brace and the king-post.

7. The combination with the corner-post,

a brace, and a king-post, of a block, an abutment on the block against which the brace ¹⁵ bears, a wedge driven between the block and the king-post, an anchor, a cable connecting the anchor and the brace, and a cable connecting the anchor and the king-post.

The foregoing specification signed this 1st ²⁰ day of September, 1902.

EDWARD G. ^{his} X HORNE.
